UNITED STATES PATENT OFFICE.

WILLIAM C. ELLIS, OF RISING SUN, INDIANA, ASSIGNOR TO HIMSELF AND
WILLIAM F. SMELLEY, OF SAME PLACE.

BALING-PRESS.

SPECIFICATION forming part of Letters Patent No. 372,901, dated November 8, 1887.

Application filed July 7, 1887. Serial No. 243,622. (No model.)

To all whom it may concern:

Be it known that I, WILLIAM CURTIS ELLIS, of Rising Sun, in the county of Ohio and State of Indiana, have invented a new and Improved 5 Baling-Press, of which the following is a full, clear, and exact description.

My invention relates to baling-presses, and has for its object to provide a simple, inexpensive, durable, and efficient machine of this 10 character adapted for a wide range of work in pressing hay, straw, cotton, or other material which may be baled by it with economy of time and labor.

The invention consists in certain novel features of construction and combinations of parts of the baling-press, all as hereinafter described and claimed.

Reference is to be had to the accompanying drawings, forming a part of this specification, 20 in which similar letters of reference indicate corresponding parts in all the figures.

Figure 1 is a plan view of my improved baling-press. Fig. 2 is a side elevation thereof with a sweep arranged below the press in 25 dotted lines. Fig. 3 is a vertical central longitudinal section of the press; and Fig. 4 is a transverse section taken on the line *xx*, Fig. 3.

The press-case A is made with a base or sill portion, *a*, which extends beneath the power 30 mechanism, the plunger-beam B, and the baling-box and chamber C, in which box the plunger D operates to press the bales, as presently described. The upper wall, *a'*, of the press-case is provided with an opening, *c*, 35 through which the material to be baled is fed into the baling-box C, in front of the draw-back plunger, and the rear end of the case is formed as a door, E, which may be opened to discharge the bales after they have been tied 40 by wires or bands introduced at the ordinary slots, *e*, made in the sides of the case and in the plunger and the door; or they may be in spacing-blocks placed in the bale-chamber.

Between the baling-box C and the front portion 45 of the press-case its upper and side walls are cut away to provide an opening or gang-way, F, across which and approaches *ff*, leading to it, the animal hitched to the sweep G may travel as he walks around to apply the power 50 for pressing the bales.

To the plunger-beam B are fixed a couple

of blocks, H H, to which an upper plate, I, is fixed, thereby providing between the parts B I a space in which operate the main drive-wheel J, to the shaft K of which the power-sweep G is attached, and two anti-friction wheels, L L, against which the wheel J acts to move the plunger-beam and plunger backward and forward in the press-case. The shaft K is journaled in the top and bottom 60 walls of the press-case, and the rollers L L are journaled in the parts B I and move with them, and these parts B I are slotted at *b i*, respectively, where the shaft K passes through them to allow movement of the plunger-beam 65 and plunger by the wheel J, which is mounted eccentrically on its shaft K, as shown in Figs. 1, 2, and 3 of the drawings. The opposing faces of the parts B I and the adjacent bottom and top walls of the press-case are provided 70 with longitudinally-ranging tongue-and-groove joints, as shown at M in Fig. 4, and whereby the entire plunger will be guided in its movements. It is obvious that as the sweep G is turned around in either direction the cam-wheel J will be rotated and the plunger-beam 75 and plunger will be reciprocated in the case to press material fed into the baling-box. It will be noticed that the plunger and its beam are connected directly with the power mechanism, whereby the power is applied with minimum friction and strain and by the use of but few parts, which insures maximum strength and durability of the entire machine. Furthermore, the simple construction allows the 80 drive-wheel shaft K to be extended below the sill of the press-case and through the floor of a barn on which the press-case may rest, to allow the sweep G to be connected to the shaft in the cellar of the barn, as indicated in dotted 85 lines in Fig. 2 of the drawings, and whereby the animals working the press may walk in the cellar and entirely out of the way of the attendants of the press while operating the press to as great advantage as when traveling 90 on the floor on which the press-case rests.

The press may be mounted on a wheeled truck of any approved construction, as will readily be understood.

Having thus described my invention, what 100 I claim as new, and desire to secure by Letters Patent, is—

The combination, in a baling-press, with the grooved sill a' and tongued sill a , forming the casing A , of the baling-chamber C , the gangway F , having approaches f , interposed between said casing and chamber, the grooved reciprocating beam B , extending from casing A into chamber C below said gangway, and carrying a follower, the blocks H H , tongued plate I , the anti-friction rollers L L , journaled

in said plate I and beam B , and the eccentric wheel J , journaled in the case between plate I and beam B and acting on said anti-friction rollers, substantially as set forth.

WILLIAM C. ELLIS.
